VENETIAN BLIND

Nicolas Musheli, Buenos Aires, Argentina

Application April 17, 1952, Serial No. 282,771

5 Claims. (Cl. 160—168)

The present invention relates to a Venetian blind made of hinged slats.

One of the objects of the present invention is to provide means for collapsing the blind so that its slats lie adjacent one another in an extremely compact arrangement.

Another object of the present invention is to provide means for collapsibly folding the blind at a central portion of the window on which it is installed so as to provide free space, light, and air both above and below the collapsed blind.

A further object of the present invention is to provide a blind, which in its completely unfolded position will completely seal the opening over which it is installed.

With the above objects in view, the present invention mainly consists of a Venetian blind arrangement comprising, in combination, support frame means including two opposite upright guide members each formed with an elongated slot, a row of substantially parallel slats of gradually decreasing length from one end slat of the blind to the other end slat of the blind, the blind being movable between a collapsed position and an expanded position, a plurality of cross fins respectively fixed to the extremities of the slats, the cross fins on the same slat being of the same dimensions and all of the cross fins extending in a direction away from the longest of the slats and having in said direction a dimension which gradually increases from the longest to the shortest of the slats, the cross fins partially overlapping each other in the collapsed position of the blind so that in the collapsed position all of the cross fins except those connected to the longest slat have portions extending beyond the preceding cross fins, and lazy tong means for moving the blind between the positions thereof, the lazy tong means including a plurality of links and a plurality of elongated connecting members for connecting individual links to each other at points thereof intermediate their free ends, at least some of said connecting members being longer than the combined thickness of the links which each respective connecting member connects to each other and being slidably arranged in one of the elongated slots of the guide members, and parallel links of the lazy tong means being connected, respectively, to the portions of the cross fins so that when the blind is in the collapsed position thereof the slats and lazy tong means together form a compact group.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a side elevational view of a Venetian blind made in accordance with the present invention, in its open position;

2

Fig. 2 is a side elevational view of the blind, in its collapsed position;

Fig. 2a is a fragmentary side elevational view of a portion of the blind in its collapsed position;

5 Fig. 3 is a fragmentary front elevational view of the same blind in its unfolded position;

Fig. 4 is a fragmentary front elevational view of the blind in its collapsed position;

Fig. 5 shows the driving mechanism of the lower shaft 10 of the blind;

Fig. 6 is a fragmentary side elevational view of the blind in its open position;

Fig. 7 is a fragmentary front elevational view of the blind in its open position;

Fig. 8 is a fragmentary side elevational view of a portion of the blind in its collapsed position;

Fig. 9 is a fragmentary front elevational view of a portion of the blind in its collapsed position; and

Fig. 10 is a plan view, partly in section, of a portion 20 of the blind.

In the following description, reference will be made to reference numerals to identify different elements shown in the drawings, it being understood that, the same reference numerals, even when used with reference to different figures in the drawings, designate the same or equivalent elements.

The blind is installed on a window 1 of the wall 2 and is formed of a plurality of slats 3 made of metallic plate, each being provided with cross fins 4 and 5 at its extremities.

Each slat carries, at its extremities, cross fins 6 of a size gradually increasing in the descending direction, which fins are secured at their free edges 7 to the parallel links 8. Each link 8 is connected to one of the cross fins 6 35 at a point 11, which represents the point of intersection of each set of cooperating links 8, 9. As is clearly shown in the drawing, the free ends of all but the last links 8 are connected to the free ends of links 9, so that the links 8, 9 together constitute a lazy tong arrangement.

As is further shown in the drawing connecting means 11' and 11" serve to connect the end links 8, 9. These connecting means 11', 11" are preferably longer than the combined thickness of the links 8, 9 which they connect to each other and are slidably arranged in elongated slots 35 16 of oppositely arranged upright guide members 15. If desired, such elongated connecting members may be provided at the midpoints of all of the links 8, 9 so that all of the connecting members are slidably arranged within one of the elongated slots 16.

50 As is clearly shown in Fig. 10 each of the elongated connecting members 11, 11' and 11" may be provided with a suitable retaining portion 23 which prevents accidental withdrawal of each connecting member from the slots.

55 Suitable drive means are provided for moving the blind to and from its collapsed position. The drive means includes endless chains 12 which are moved about upper pinions 13 and lower pinions 14. The arrangement of the parts is such that the elongated connecting members 11', 11" are connected in opposite portions of each chain 12 so that when the endless chain 12 is moved about the pinions 13 and 14, one of the connecting members will move upwardly and the other of the connecting members will move downwardly so that the lazy tong means and 60 the blind will be collapsed from both ends toward the center thereof.

65 As is best seen in Figs. 3 and 5, the lower pinions 14 are secured to a horizontal shaft 17 located within the hollow 18. This shaft carries a toothed bevel gear 19 meshing with a second bevel gear 20 secured to the shaft 21 which extends through the wall 2, and which shaft is 70

provided with a handle 22 at the end opposite to that fixed to the bevel gear 20.

It will be understood that each of the elements described above, or two or more together, may also find a useful application in other types of blinds differing from the types described above.

While the invention has been illustrated and described as embodied in Venetian blinds, it is not intended to be limited to the details shown, since various modifications and structural changes may be made without departing 10 in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

What is claimed, is:

1. A Venetian blind comprising, in combination, a row of substantially parallel slats of gradually decreasing length from one end slat of said blind to the other end slat of said blind, said blind being movable between a collapsed position and an expanded position; a plurality of cross fins respectively fixed to the extremities of said slats, the cross fins on the same slats being of the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins, respectively; and lazy tong means having parallel links thereof respectively connected to said portions of said cross fins for moving said blind between said positions so that in the collapsed position thereof the slats and lazy tong means together form a compact group.

2. A Venetian blind comprising, in combination, a row of substantially parallel slats of gradually decreasing length from one end slat of said blind to the other end slat of said blind, said blind being movable between a collapsed position and an expanded position; a plurality of cross fins respectively fixed to the extremities of said slats, the cross fins on the same slat being of the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins, respectively; lazy tong means having parallel links thereof respectively connected to said portions of said cross fins for moving said blind between said positions so that in the collapsed position thereof the slats and lazy tong means together form a compact group; and drive means coupled to the ends of said lazy tong means for simultaneously collapsing said lazy tong means from both ends thereof toward the center thereof, so as to collapse said blind.

3. A Venetian blind arrangement, comprising, in combination, support frame means including two opposite upright guide members each formed with an elongated slot; a row of substantially parallel slats of gradually decreasing length from one end slat of said blind to the other end slat of said blind, said blind being movable between a collapsed position and an expanded position; a plurality of cross fins respectively fixed to the extremities of said slats, the cross fins on the same slat being of the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins; lazy tong means for moving said blind between said positions thereof, said lazy tong means in-

the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins; and lazy tong means for moving said blind between said positions thereof, said lazy tong means including a plurality of links and a plurality of elongated connecting members for connecting individual links to each other at points thereof intermediate their free ends, at least some of said connecting members being longer than the combined thickness of the links which each respective connecting member connects to each other and being slidably arranged in one of said elongated slots of said guide members, and parallel links of said lazy tong means being connected, respectively, to said portions of said cross fins so that when said blind is in said collapsed position thereof the slats and lazy tong means together form a compact group.

4. A Venetian blind arrangement, comprising, in combination, support frame means including two opposite upright guide members each formed with an elongated slot; a row of substantially parallel slats of gradually decreasing length from one end slat of said blind to the other end slat of said blind, said blind being movable between a collapsed position and an expanded position; a plurality of cross fins respectively fixed to the extremities of said slats, the cross fins on the same slat being of the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins; lazy tong means for moving said blind between said positions thereof, said lazy tong means including a plurality of links and a plurality of elongated connecting members for connecting individual links to each other at points thereof intermediate their free ends, at least some of said connecting members being longer than the combined thickness of the links which each respective connecting member connects to each other and being slidably arranged in one of said elongated slots of said guide members, and parallel links of said lazy tong means being connected, respectively, to said portions of said cross fins so that when said blind is in said collapsed position thereof the slats and lazy tong means together form a compact group.

5. A Venetian blind arrangement, comprising, in combination, support frame means including two opposite upright guide members each formed with an elongated slot; a row of substantially parallel slats of gradually decreasing length from one end slat of said blind to the other end slat of said blind, said blind being movable between a collapsed position and an expanded position; a plurality of cross fins respectively fixed to the extremities of said slats, the cross fins on the same slat being of the same dimensions and all of said cross fins extending in a direction away from the longest of said slats and having in said direction a dimension which gradually increases from the longest to the shortest of said slats, said cross fins partially overlapping each other in the collapsed position of said blind so that in said collapsed position all of said cross fins except those connected to the longest slat have portions extending beyond the preceding cross fins; lazy tong means for moving said blind between said positions thereof, said lazy tong means in-

cluding a plurality of links and a plurality of elongated connecting members for connecting individual links to each other at points thereof intermediate their free ends, a set of said connecting members at the ends of said lazy tong means being longer than the combined thickness of the links which each respective connecting member connects to each other and being slidably arranged in one of said elongated slots of said guide members, and parallel links of said lazy tong means being connected, respectively, to said portions of said cross fins 10 so that when said blind is in said collapsed position thereof the slats and lazy tong means together form a compact group; and drive means coupled to said set of connecting members at the ends of said lazy tong means for

simultaneously collapsing said lazy tong means from both ends thereof toward the center thereof so as to collapse said blind.
